UNITED STATES PATENT OFFICE

2,102,548

APPARATUS FOR TREATING HYDRO-CARBON OILS

Charles W. Stratford, Kansas City, Mo., assignor
to Stratford Development Corporation, Kansas
City, Mo., a corporation of Delaware

Application March 27, 1935, Serial No. 13,219

7 Claims. (Cl. 196—46)

My invention relates to apparatus for treating hydrocarbon oils and more particularly to a contactor for contacting a hydrocarbon oil with a treating agent, as for example, acid.

5 A contactor is a mechanical mixer, the construction of which has for its purpose to intimately contact two liquids or a liquid and a finely divided solid. A good contactor provides for infinite dispersion and maximum intimacy of contact. This is best accomplished by frequent and forced changes in velocity and direction of flow.

10 In the treatment of hydrocarbon oils with a treating agent as for example acid, the time of contact between the acid and the oil being treated is of great importance in order to secure the best 15 treating results. By way of clarification and not by way of limitation, the following example is given. When treating a pressure distillate containing a large percentage of sulphur bodies at atmospheric temperature (70° F.) with relative 20 large quantities of acid (approximately 12 pounds of 98 percent sulphuric acid), the total contact time between the acid and the distillate must not exceed one second. It has been found that a contact time in excess of this period will result in 25 polymerization losses and further losses of distillate by dissolution in the concentrated sulphuric acid. The polymerization losses and distillate losses will be so excessive that the treating process 30 will be uneconomical. In the above example, if the temperature of the pressure distillate were reduced, the contacting time could be lengthened.

35 Still by way of example, in the treatment of lubricating oil distillates with sulphuric acid, it is usually necessary to heat these to a temperature of in the neighborhood of 180° F. in order to reduce their viscosity to such a point that they may be dispersed and homogenized with acid. The contact time which is permissible in the treatment 40 of lubricating oil distillates with sulphuric acid may be as long as 300 seconds. It will readily be understood by those skilled in the art that the contact time is usually a function of the strength and quantity of the acid, the particular hydro- 45 carbon oil being treated and the temperature at which the treating process takes place.

50 The difficulties encountered in acid treating in refinery operations and the unsatisfactory results which are often attained for a given hydrocarbon distillate are caused chiefly by the employment of improper contact times for the treating temperature employed, and the strength and quantity of the treating acid.

55 It will also be readily understood that, unless uniform and homogeneous mixing of the treating

agent and the hydrocarbon oil being treated is obtained, the determination of the proper contact time is impossible.

The temperature in treating processes can be 5 readily controlled by heat exchange. The chemical composition of a particular distillate to be treated can be ascertained and is more or less constant. The strength of the acid, if acid is the treating agent to be employed, can also be governed and maintained at a uniform point. We 10 have then two variables which must be controlled in order to get proper results. These are uniformity of dispersion or mixing of the treating agent with the distillate to be treated, and the contact time during which the acid and the distillate are to remain in intimate contact with each other.

I have given a case of contacting hydrocarbon distillates with acid by way of example. It is to be understood that any of the treating agents 20 known to the art which are or may be suitable for the treatment of hydrocarbon oils, may be employed in my apparatus. For example, sulphur dioxide, either alone or in combination with benzene, chloroform, or the like, nitrobenzene, phenol, dichlor ethyl ether, furfural, propane, mixtures of propane with selective solvents such as methyl ethyl ketone, or the like, may be employed. Likewise, solutions of metallic salts or metallic oxides as well as caustic solutions may 30 be intimately mixed with hydrocarbon oils in my apparatus. Similarly, oils may be blended and addition agents may be added to oils by means of my apparatus. For example, pour point depressants like the condensation product of a chlorinated aromatic hydrocarbon and a chlorinated wax may be intimately mixed with hydrocarbon oils by means of my apparatus. Similarly, film 35 strength and oiliness characteristic improvers may be blended with hydrocarbon oils in my apparatus. For example, chlorinated diphenyl which is a film strength improver may be intimately mixed with hydrocarbon oil by means of my apparatus. Likewise, esters of organic acids 40 may be mixed with hydrocarbon oils as oiliness 45 improvers.

One object of my invention is to provide a mechanical mixing device whereby intimate mixtures of liquids and/or liquids and finely divided solids, as for example diatomaceous earth, bentonite, fuller's earth, tripoli, and other filter aids, 50 may be intimately mixed and uniformly dispersed through the liquid.

Another object of my invention is to provide a mechanical mixing device in which the time of

contact may be readily controlled and adjusted.

Another object of my invention is to provide a mechanical contacting device in which the volume of the apparatus may be varied in order to provide a time interval of contacting which is adjustable.

Another object of my invention is to provide a mechanical contacting device which will prevent the emulsification or incorporation of air and/or gas with the liquid being contacted in my apparatus.

Other and further objects of my invention will appear from the following description.

In general, my invention contemplates the provision of a circular impeller for establishing a zone of high turbulence and providing stationary shearing blades above the impeller and diffuser vanes below the impeller. The impeller establishes a rapid flow of liquid in a short, continuous path. The direction of flow is constantly being changed and the velocity of flow is constantly being altered so that frequent enforced changes in velocity and direction result. The volume of liquid within the contacting zone is governed by an adjustable means.

In the accompanying drawing, which forms part of the instant specification and is to be read in conjunction therewith and in which like reference numerals are used to indicate like parts in the various views;

Figure 1 is an elevation partly in section, of an apparatus embodying one mode of carrying out my invention.

Figure 2 is an elevation of the lower part of the apparatus shown in Figure 1, with part of the exterior casing broken away.

Figure 3 is a sectional view taken on the line 3—3 of Figure 1.

Figure 4 is a sectional view taken on the line 4—4 of Figure 1.

Figure 5 is a sectional view taken on the line 5—5 of Figure 1.

More particularly referring now to the drawing, a shell is formed with an upper cylindrical portion 1 and a lower portion 2, which is made in the form of a truncated cone. The lower portion 2 is provided with a spaced shell 3 forming a jacket in which is provided a suitable baffle, as for example spiral baffle 4. Suitably supported from shell 1 is a driving motor 5 which is connected to shaft 6, which is housed in a tube 7. The end 8 of shaft 6 is guided by a bushing 9 in the lower portion of the apparatus. Keyed to shaft 6 in any suitable manner is an impeller 10. It will be observed that, by putting the driving motor at the top, leakage and difficulties which would otherwise be encountered by a bottom stuffing box are avoided. This is especially advantageous if acid is used as a treating agent.

Within the lower portion 2 of the shell and spaced therefrom, I provide a baffle 11 in the form of a truncated cone. The shell 2 and the baffle 11 form an annular passageway of progressively increasing cross sectional area. Within this passageway I position a plurality of vanes 12 which extend longitudinally. Lying longitudinally along the interior surface of baffle 11 and extending radially, I provide a plurality of vanes 13. Directly above the impeller 10 I provide a plurality of shearing blades 14. Directly below the impeller 10 I provide a plurality of diffuser vanes 15 by which the liquid is straightened into linear turbulent flow. Further vanes 16 are provided in the annular passageway formed in the lower portion of my contactor. A lubricating device 17 is

provided for lubricating the lower portion 8 of the shaft 6. A plurality of manifolds 18 having branch pipes 19 communicating with the interior of shell 1 are provided as can readily be seen by reference to Figure 1. These manifolds are the outlet manifolds. Each manifold is provided with a plug cock 20 which controls communication of each manifold with a header 21. Positioned within the cylindrical portion 1 of the shell 1 provide a float 22 which is made up of a plurality of segments secured to each other by flanges 23 in any suitable manner. In its lowest position, with my apparatus empty, the float rests upon stops 24. The float may be made of steel or any other suitable material. A wire cable 25 passes through stuffing box 26 over pulleys 27 and is secured to an indicator device 28 which is adapted to ride in a guideway 29 secured to the exterior of the shell 1. It will be obvious that, as the float 22 rises, the indicator button 28 will drop indicating the position of the float within the shell. The liquids to be mixed are charged to the contactor through inlet nozzle 30, an inlet pipe 31 being provided interiorly to conduct the liquids to be mixed to a point near the axis of my apparatus.

By introducing the liquids to be mixed or contacted in this manner into the suction of the impeller, there is no danger of having materials which are not thoroughly mixed overflowing through the outlet manifold. It will be noted that the outlet manifolds are positioned to skim the mixture from the very outside of the shell at points where the mixture is intimate and homogeneous. A number of eduction points are provided around the shell to avoid the withdrawal of a mixture from entirely one point, thus avoiding the short circuiting of unmixed liquids. The plug cocks 20, 20a, 20b, and 20c determine the level which the float will assume. For example, if plug cock 20c were opened, the liquid would pass into the eduction header 21 through the lowermost circular manifold. If plug cocks 20a, 20b, and 20c were closed, the float would assume its uppermost position and the liquid would be withdrawn through circular manifold 18. A gas vent 32, controlled by a valve 33 is provided. Drain pipe 34 controlled by plug cock 35 is provided for draining the apparatus. A heating or cooling medium may be supplied to the jacket through connection 37 and withdrawn through connection 38.

In operation, the volume of the contacting zone desired for the particular treatment to be practiced having been determined, the proper plug cock 20, 20a, 20b, or 20c is opened and the others closed. The liquids to be mixed are supplied through inlet 30. The motor 5 is started. The liquids to be mixed will flow downwardly at constantly increasing velocity due to the fact that the baffle 11 is provided with a progressively decreasing cross sectional area. The impeller 10 discharges the liquid downwardly. The mixture is forced to change its direction 180°, the vanes 15 imparting to it a straight line turbulent flow. Vanes 16 and 12 prevent a tendency toward whirling. In the annular jacket formed by the shell 2 and the baffle 11, the mixture will flow at a constantly decreasing velocity due to the fact that the cross sectional area of the annular passageway is constantly increasing. The vanes 13 in the interior of baffle 11 also prevent a tendency toward whirling. The float 22 excludes all air, vapor and/or gas, preventing cavitation and precluding the formation of gas and/or air emulsions. It is to be noted that, if

air is present, the resulting oxidizing reaction will accelerate the formation of polymers. The float prevents this oxidation. If air and/or gas-oil emulsions are formed, the subsequent separation of the treating agent is greatly impaired. The intimately contacted mixture is withdrawn through its manifold and discharged through header 21 to centrifuges in which centrifugal separation of the treating agents is effected.

10 It will be observed that I have accomplished the objects of my invention. I have provided a mixing apparatus which permits easy variation of volumetric capacity. By means of the control which I am able to exercise over the volumetric capacity, I can control the time of contact of the material undergoing mixing. I have provided a sealing float for the protection of the upper surface of the liquids undergoing mixing precluding the formation of gas and oil, 15 or air and oil emulsions with the resulting oxidation which would otherwise ensue. The jacket provides a means for easily controlling the temperature of the contacting operation. The flow of the liquids to be mixed is such that the velocity 20 and direction of flow are constantly being varied which, together with the float which acts as an anti-cavitation means makes my contactor a very efficient one. It is to be understood that my contactor may be used for any desired process 25 in which liquids and/or liquids and finely divided solids are to be contacted and formed into homogeneous mixtures.

It will be understood that certain features and subcombinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I 45 claim is:

1. In an apparatus for contacting a treating agent with a hydrocarbon oil, a shell comprising an upper cylindrical portion and a lower conical portion, a conical baffle within said lower portion 50 and spaced therefrom to define an annular passageway of progressively increasing cross-sectional area, an impeller mounted within said shell adapted to circulate liquid from within said baf-

fie and to discharge the same through said annular passageway, a floating dam within said cylindrical portion, an inlet to said shell for the treating agent and the oil, a plurality of drawoff connections communicating with the interior of 5 said shell at a plurality of vertically spaced points and means for controlling said drawoffs.

2. In a contacting apparatus, a vertical shell formed with a lower tapered portion, a liquid inlet to said shell, a tapered baffle within said lower portion spacedly mounted therefrom to form a passageway of progressively varying cross-sectional area, an impeller mounted within said lower portion for circulating liquid within said shell through said passageway, a floating 15 dam mounted within said shell, and a plurality of selective drawoffs from said shell.

3. In a contacting apparatus, a vertical shell formed with a lower portion enclosing a space of decreasing cross-sectional area, a baffle mounted 20 within said shell in spaced relation thereto and forming a passageway therewith, an impeller mounted within the shell and adapted to discharge liquid through said passageway and piston means for varying the volume of said shell above 25 said impeller.

4. In a contactor, a shell, a liquid inlet means into said shell, a liquid drawoff means communicating with the interior of said shell, an agitating means within said shell, and piston means 30 within said shell above said agitating means for varying the volumetric capacity of said shell.

5. In a contactor, a shell, a liquid inlet means, a plurality of liquid drawoff means, an agitator within said shell, and a piston means within said shell above said agitator adapted to prevent cavitation of the liquid due to the operation of said agitator.

6. A contactor having a shell, an agitator there-within, piston means within said shell above said agitator to vary the volumetric capacity of said shell and means for controlling the temperature of the liquid being contacted.

7. In a contactor, a shell, a liquid inlet means into said shell, a liquid drawoff means communicating with the interior of said shell, an agitating means within said shell, means for controlling the temperature existing within said shell, and piston means within said shell above said agitating means for varying the volumetric capacity 50 of said shell.

CHARLES W. STRATFORD.
